UNITED STATES PATENT OFFICE.

JAMES H. MUNRO, OF PEN ARGYL, PENNSYLVANIA.

COVERING.

1,250,623.

Specification of Letters Patent. Patented Dec. 18, 1917.

Application filed November 19, 1912, Serial No. 732,319. Renewed May 14, 1917. Serial No. 168,591.

To all whom it may concern:

Be it known that I, JAMES H. MUNRO, of Pen Argyl, Pennsylvania, have invented certain Improvements in Coverings, of which the following description, in connection with the accompanying drawings, is a specification, like characters on drawings designating like parts.

This invention relates to coverings for roofs and other surfaces, and is of special utility when embodied in construction of covering units possessing some of the properties of roofing tiles, as, for example, the ease with which they may be handled, their durability, and their weather-proof and fire-proof qualities, it being understood however that I contemplate the utilization of my improvements in any field for which they are adapted by their nature.

An important object of my invention is to provide a roof covering of the type in which a foundation of concrete or boards, known as the "roof deck" is provided with what is known to the trade as a "built-up water-proofing" composed of several layers of tar paper cemented together with hot pitch and laid over the foundation, this built-up water-proofing being usually covered by tiles cemented to the water-proofing with a mastic or bituminous material or embedded in Portland cement concrete, but my improved roofing being free from the serious objections to existing methods which result from the expansion of the tile and concrete in very hot weather, acting either to force out the wall or the parapet of the roof, or else to cause a bulge or blister of the tiling itself, breaking the continuity of the roof and destroying its water-proof character as well as destroying its smoothness for traffic. When mastic is used as the material in which to set the tiles, the heat causes the bituminous materials to expand between the tiles and to come above the tiles in narrow rolls which are kicked off because they do not retire again into place, and then when contraction takes place in cold weather there are voids left in many places sufficient to allow water to get down under the tile and there freeze, lifting the tile up and making the roofing uneven.

Where a cement concrete has been used as the layer in which the tiles are to be em-

bedded, there is no affinity between this cement and the bituminous materials of the water-proofing, so that the cement bed for the tiles does not constitute a unitary structure with the water-proofing but simply lies thereupon by reason of its weight, so that water, which gets beneath the same, will freeze in winter and lift the cement bedding.

In contra-distinction to the above structures, and in order to overcome the objections above noted, I provide a thin sheet of pre-cured cement, made of any desired shape or size, to serve as an anchorage stratum in the later application of the surface covering proper, whether the latter be a layer of tiles embedded in cement secured to the anchorage, or whether, in accordance with another important feature of my invention, the surface covering consists of a sheet or sheets of cement applied to the anchorage.

In accordance with my invention, I unite the anchorage sheet of thin pre-cured cement to the built-up water-proofing, such as that above described, with the same bituminous materials used in ordinary practice, so that it will become part of the water-proofing and makes it impossible for water to get beneath the anchorage. I may also nail this thin anchorage sheet of concrete, through the water-proofing to the deck, preferably using for this purpose the well known short thick steel nails employed for similar purposes.

Where the surface to be covered is of such area that provision should be made for expansion of the covering, I prefer not to place these anchorage sheets close together but to space them apart by suitable means, as, for example, a temporary strip of wood, but I prefer to use as the spacing device strips of flexible bituminous material, the height of the spacing strips being that of the covering when finished.

This anchorage sheet of cement is not only united to the water-proofing in the above described manner, but it serves also as a perfect anchorage for the cement thereafter used as a bed for the tiles or for securing any desired surface covering members, which may, as above noted, take the form of sheets of pre-cured cement, similar to those

of the anchorage layer, and accordingly the anchorage layer and the surface layer become one solid mass of homogeneous material.

- 5 To facilitate this action, I prefer to make the anchorage sheets rough upon their upper surfaces, either by means of a series of keys or dovetails, to engage with the cement mortar used as a bed for the tiles or to se-
- 10 cure the surface sheets of pre-cured cement; or the anchorage layers may have hair or fibers projecting to engage the cement mortar, and if the surface sheets of this cement are utilized, I prefer to have their back
- 15 rough similarly to engage the cement mortar. One or both of said sheets, that is the wearing surface of the top sheet of concrete, is preferably made of water-proof concrete to prevent the absorption of moisture;
- 20 also to prevent the evaporation of the cement mortar used to unite the layers until the cement mortar shall have been thoroughly cured and hardened.

This cement mortar may be of any suitable material, as, for example, Portland cement, or a bituminous cement.

By the use of an anchorage layer formed of these sheets of concrete, I am enabled to adapt my improved covering readily to any contour, so that a very uneven roof can be readily provided with a thoroughly water-proof and fire proof covering, inasmuch as when the surface covering of concrete or tiles has been applied to the anchorage layer, in accordance with my invention, the completed covering constitutes a solid concrete slab made of any desired thickness or size, and the deck surface need not require any finishing work after being laid, because the desired finish can be provided in the course of manufacture at the factory, or wherever the sheets or sections have been made.

The object of the small dividing strip placed between the sections is to keep the rigid tile and cement apart and make provision for expansion, and for this purpose the strip may be taken out, if a temporary strip has been used and the space filled by pouring in the hot bituminous cement or by filling the joint up with roofing cement; or use may be made, as already noted, of a small bituminous strip, of the desired height and thickness, set in place when the anchorage layer of thin concrete is being cemented to the water-proofing with the bituminous material.

The various features of my invention will be illustrated and described fully in the accompanying drawings and specification and set forth in the claims.

In the drawings,

Figure 1 is a view in plan of part of a roof in the construction of which my invention has been embodied;

Fig. 2 is a view in vertical section taken

on the line X²—X² in Fig. 1, on an enlarged scale;

Figs. 3 and 4 are views in fragmentary form, similar to Fig. 2, of modified forms of anchorage layers;

Fig. 5 is a view of a modified covering, upon a roof, in vertical section showing a curve at the eaves.

In the embodiment of my invention selected for illustration and description to enable ready and complete understanding of my improvements, the parts designated by the reference numeral 1 are sheets of thin pre-cured cement which, in accordance with my invention, constitutes a portion of an anchorage layer, superimposed in the instance illustrated by way of example upon water-proofing 2 consisting of one or more layers of prepared paper cemented with hot pitch upon the roof deck 3 formed of a foundation of boards 4 (see Fig. 2), or, as indicated therein at 5, of concrete.

The anchorage sheet 1 is preferably secured to the built-up water-proofing by hot pitch, or similar bituminous material 6 so that it becomes a part of the water-proofing and no water can get under it, and it may also be secured by suitable fastening devices, as the nails 8.

When the area is such as to make it desirable to provide for expansion, the sheets 1 are preferably spaced apart, for which purpose use may be made of any suitable means to insure uniformity of spacing, as, for example, a temporary strip of wood 10 of the height of the finished roofing, or strips of flexible bituminous material may be used as shown at 12, forming a permanent part of the finished roofing. At 14 I have shown a space formed by use of one of the wooden spacing strip 10, and thereafter filled with a suitable filling, such as a bituminous roofing cement.

In accordance with an important object of my invention the covering may be completed by cementing to the anchorage layer 1 a suitable surface layer 20, preferably of refractory materials, with a bedding 30 of a cementitious substance suitable to unite with the anchorage layer 1 and surface layer 20 to form therewith a unitary structure of the nature of a concrete block, so that the resultant covering presents a waterproof and fireproof surface structure firmly united to the roof-deck and capable of resisting the intrusion of moisture with consequent damage by frost. The surface layer 20 may be of any suitable composition, as for example comprising tiles 21 or sheets 210, as indicated in Fig. 1 diagrammatically, and more in detail in the subsequent figures, to be described.

To provide for the desired union between the anchorage, bedding and surface layers, any suitable construction of the respective

layers may be adopted, and as one convenient form of such structure I have shown in Fig. 2 an anchorage layer comprising bar-like members 26 of cement concrete, molded upon a vehicle 27 of suitable material, such as burlap or unwoven fibers if it is desired to have the sheets flexible, the proximate margins 28 of the bars being preferably molded to constitute overhanging keys, between which the material of the bedding layer 30 preferably enters at the time of its application in plastic state, forming tenons 31.

Other forms of bonding may be adopted, as found desirable, for example by forming the anchorage sheets in the shape of dovetail bars 260, as shown in Fig. 4, in staggered relation on each side of a sheet of fabric 270, so that the waterproofing cement 60 enters from below to form tenons 66, and the bedding cement 30 enters from above to form tenons 33. So, also, in Fig. 3, the bonding is provided for by fibers 34 sown in the cement anchorage layer 11, and entering the bedding layer 35. If desired, the anchorage layer may be relatively inflexible, as in the instance shown by way of example at 11, although if fractured the fibers will tend to hold together the broken parts.

By the use of a flexible anchorage layer 1, however, I have provided means to compensate for considerable irregularities of contour in the built-up waterproofing 2, whether due to its structure or that of the underlying roof-deck 3, so that however wavy may be the anchorage layer 1, its function of providing intimate union with the built-up waterproofing 2, below, and with the surface layer 20, above, is not impaired, since the bedding layer 30 of cementitious substance is bonded at 31 to the anchorage layer 1, however irregular the latter, and the cementitious layer 30 affords a perfect bedding for a level surface layer 20, however the latter may be constituted, and in the selection of materials therefor a wide choice is permissible.

By way of example, I have shown in Fig. 2 a surface layer of tiles 21 of refractory material, such as baked clay, set in the bedding 30 of Portland cement concrete, and grouted as usual at 25, with occasional expansion joints as at 12 or 14, already described, if the area of the covering warrants the provision for expansion. Thus, we have a perfectly solid block composed of the tiles 21, presenting a level, wear-proof surface, inalterable by frost, and impermeable by moisture, while the under surface of the tile is in permanent union with the waterproofing and corresponds exactly in contour with the supporting deck, these advantages being secured by the provision of my novel anchorage layer 1, which can

be laid easily and quickly over large surfaces, being transportable in flat or rolled sheet units of extensive size.

No specially skilled workmanship is necessary for its installation; its uniformity of quality can be insured by making and procuring it under favorable conditions with skilled labor at the manufactory, and after it has been laid the completion of the covering by applying the bedding 30 and the tiles 20 can be accomplished quickly by workmen of average skill, no special instruction being required, as the bonding at 31 effects itself automatically.

One of the most important features of my invention, is the further combination of these flexible sheets which I have devised, and of which an example is illustrated in Fig. 5, where the surface layer 20 comprises a sheet of flexible stone concrete formed of members 26 as already described and laid upon the bedding 30 after the latter has been applied in plastic form to the anchorage layer 1, superimposed upon the built-up waterproofing 2 supported by the roof deck 3, the fastening means comprising bituminous cement and nails 8, either or both, in the instance illustrated.

By this combination of sheets 1 and 20 in the inverted relation illustrated, the bedding cement 30 is admitted to form tenons 31 in union with each of the layers, and where the bedding layer 30 is of oleaginous material it is prevented from drying out, the surface layer 20 being continuous in the instance illustrated, and preferably formed of waterproof cement, felted with fibers at the surfaces.

This type of combined flexible layers is particularly useful for application to surfaces presenting abrupt changes of contour, as to the curved gutter above the eaves of a roof, represented at 40, in Fig. 5, where the bars may be narrower.

The completed covering constitutes a solid cement block in which the flexible elements 1 and 20 and the plastic element 30 have lost their formative characteristics, and together make a rigid, homogeneous, unitary structural member united permanently to the roof deck, in such a manner as to prevent intrusion of moisture beneath the block, and presenting a wear proof surface likewise impervious to water. Expansion joints may be provided at suitable intervals between adjacent units, and at 42 one such joint is illustrated by way of example, filled with a suitable roofing cement, preferably of a bituminous character.

Having illustrated and described my invention thus fully, and suitable means by which the same may be carried into effect, I wish it understood that I do not limit myself to the specific materials and forms of construction selected for illustration and de-

scription by way of example, nor in general do I limit myself otherwise than as set forth in the claims read in connection with this specification.

5. What I claim as new and desire to secure by Letters Patent of the United States of America is:

1. The combination with a foundation, of a flexible pre-cured cement covering unit constituting a portable structural element secured upon said foundation and serving as an anchorage; a bedding layer of cementitious material upon said cement anchorage; and a second portable, flexible pre-cured cement covering unit embedded in said cement bedding and constituting a surface element of the unitary, cement, covering-structure comprising said anchorage, bedding and surface elements.
10. 2. The combination with a roof-deck comprising wooden members, and a waterproofing upon said deck comprising laminæ of fibrous material secured together by a pitchy

or bituminous cement, of an anchorage layer of stonelike cement secured by nails passing through said waterproofing into said wooden members, and united to said laminæ by said bituminous cement to form part of said waterproofing, said anchorage layer comprising a plurality of sheets of slats formed of precured cement mounted on a flexible vehicle and laid in abutting relation with intervening spaces for expansion joints; strips of bituminous material in said joints, of the height of the finished roofing, and a top layer comprising sheets of precured cement spaced like said anchorage sheets and secured thereto by plastic cement to form a series of unitary cement blocks.

Signed at Newark in the county of Essex 40 and State of New Jersey, this sixth day of November, 1912.

JAMES H. MUNRO.
